(57) **CLAIM**

The ornamental design for a leash, as shown and described.

DESCRIPTION

FIG. 1 is a perspective view of a leash according to a first embodiment of the invention;

FIG. 2 is a top view of the leash of FIG. 1;

FIG. 3 is a front view of the leash of FIG. 1; and,

FIG. 4 is a right side view of the leash of FIG. 1.

The features shown in broken lines are for illustrative purposes only and form no part of the claimed design.
